UNITED STATES PATENT OFFICE.

SAMUEL STEWART, OF NEWARK, NEW JERSEY.

GAS-BURNER.

No. 853,654.

Specification of Letters Patent.

Patented May 14, 1907.

Application filed March 24, 1905. Renewed March 22, 1907. Serial No. 363,955.

To all whom it may concern:

Be it known that I, SAMUEL STEWART, a citizen of the United States, whose residence is 151 Sherman avenue, Newark, county of Essex, and State of New Jersey, have invented certain new and useful Improvements in Gas-Burners, fully described and represented in the following specification and the accompanying drawings, forming a part of the same.

The present invention relates to a burner which is adapted for use in gas stoves of various kinds, and may be used effectively in gas ranges and in stoves for heating ordinary apartments.

The invention is especially applicable to a certain cheap form of heating gas-burner consisting of a plain cylindrical shell with a perforated flame-screen at the top and a gas supply pipe extended across the bottom. Heretofore, such burners have been left open at the bottom and liable to the intrusion of dirt and lint and to the disturbance produced by sudden drafts of air, and the invention consists in a cylindrical strainer made separate from the burner shell and telescopically connected therewith, and operating to wholly close the bottom of the burner so as to prevent the access of drafts and lint. In burners of this class, the flame-screen has heretofore been flanged over upon the top of the shell, or has been fitted tightly within an encircling collar; either of which constructions prevents its free expansion and causes such movements as to crack the perforated metal.

The present invention includes a particular means of supporting the edge of the flame-screen movably between two flat flanges, so as to permit free expansion and contraction.

The invention will be understood by reference to the annexed drawing, in which

Figure 1 is a vertical section of the burner and its gas supply pipe with a section of a grid for supporting cooking utensils. Fig. 2 is a side elevation of the shell; Fig. 3 a side elevation of the strainer; and Fig. 4 a plan of the burner.

a designates the cylindrical shell having a narrow flange b turned inwardly at the top to support the flame screen c which is preferably made of finely perforated sheet metal. A collar d is shown fitted to the exterior of the shell at the upper end, and provided with flange e overlapped upon the edge of the screen c to hold it upon the flange b, and the shell and collar are shown locked

together by the double bead f, f', which in practice is formed simultaneously in the shell and collar by suitable beading tools after the screen and collar are adjusted in place.

The screen has heretofore been flanged to the shell or fitted snugly within a collar which does not permit any expansion of the screen when heated, and thus causes the screen to buckle or split under repeated heating and cooling. In the present construction, the screen is made small enough to expand without interference from the collar d, and is thus capable of expanding and contracting between the flanges b and e without any injury.

The clamping of the edge of the screen between the flanges b and e and the securing of the collar by the bead f, f', prevents any leakage of air at the margin of the screen, which has been found in practice to be detrimental to the operation of the burner.

A gas pipe g is shown extended across the bottom of the shell and is provided with a single jet aperture h, which discharges gas upwardly within the shell.

The strainer which is applied to the bottom of the shell wholly closes the same, but furnishes the necessary supply of air thereto. In this class of burner, I employ a volume of air about fifty times greater than the volume of gas which is admitted, and in order to admit such a volume of air through a strainer, a large area of the strainer surface is required, and such large area I obtain by extending a cylindrical strainer downward from the shell and furnishing the same with a perforated bottom. The strainer has a perforated cylinder k having holes l at opposite sides to hang it upon the transverse gas pipe g, and it may be fitted snugly to either the inner or outer side of the shell. Such mode of fitting the strainer to the shell forms what is termed a "telescopic" connection. It is shown extending below the gas pipe nearly half as far as the shell extends upward therefrom, and a perforated bottom k' is applied to the strainer and secured thereon by flange m.

To apply the shell readily to the gas pipe, and to remove the same at pleasure to clean out its interior, or the interior of the strainer when necessary, the opposite sides of the shell are formed with slots n adapted to straddle the gas pipe g and to thus rest removably thereon. The telescopic connection between the shell and strainer makes a

joint to prevent the admission of air; while it readily permits the separation of the shell from the strainer when required, for cleaning the interior of the parts. It also permits the parts to be made interchangeable and fitted together with the least possible labor, as no fastenings of any kind are required.

This construction is very cheap and simple, and furnishes a means of securing the strainer, the shell, and the gas pipe together, without any fastening devices.

The entire construction is of a character that permits all the parts to be made by ordinary tinsmiths' tools, and enables them to be assembled with the smallest amount of labor.

It will be observed that in the burner to which this invention relates, the burner shell and its attachments may be wholly suspended upon the gas pipe *g*, so that the pipe may serve as the sole means of sustaining the burner. The burner may, therefore, be termed a "suspended burner," as it is practically hung upon the pipe, and where it projects above the pipe may be steadied by any suitable means if required.

It will be noticed that the shell *a* is wholly imperforate, and the air is admitted through the strainer wholly below the point where the gas enters the burner shell from the jet aperture *h*, as the gas pipe is located at the junction of the shell and strainer, and the air and gas are therefore mingled within the shell *a* above the gas pipe *g*. I have made a special claim to this arrangement of the shell, the gas pipe and the strainer, as it is found very advantageous in practice.

The extension of the strainer downward from the bottom of the shell, and the formation of it with the perforated bottom *k'*, gives a very large perforated area for the admission of air. The strainer prevents drafts of air from blowing into the bottom of the shell, and thus renders the operation of the burner more uniform.

In Fig. 1, a grating *o* is shown at a suitable distance above the burner to support a kettle, sauce-pan, or cooking utensil, the flame

p being represented between the top of the burner and the grating. The burner may thus be arranged for use in cooking stoves and ranges, but when used in heating stoves it is commonly placed within a sheet metal cylinder, and the heat of the flame arranged to strike the top of the heater.

Having thus set forth the nature of the invention what is claimed herein is:

1. In a gas burner for heating purposes, the combination, with a horizontal gas pipe having a jet aperture in its upper side, of a burner shell supported thereon, and projected above the gas pipe and provided with flame-screen *c* upon the top, and a cylindrical strainer telescoping with the shell and projected below the gas pipe, and closing the bottom of the shell to exclude wind and lint from the interior.

2. In a gas burner for heating purposes, the combination, with an imperforate burner shell *a* having flame-screen *c* at the top, and a perforated strainer *k* extended below the bottom of such shell, of the gas pipe *g* inserted transversely through the shell and strainer at their junction and having the jet aperture *h* upon its upper side, whereby the air supply enters wholly below the gas supply and the air is mingled with the gas in the shell.

3. In a gas burner for heating purposes, the combination, with the gas pipe *g* having perforation *h* upon its upper side, of the cylindrical perforated strainer *k* having the holes *l* fitted to the gas pipe, the cylindrical shell *a* having the flame-screen *c* upon the top and fitted telescopically at its lower end upon the strainer *k*, and provided with the slots *n* at opposite sides fitted removably over the gas pipe, as and for the purpose set forth.

In testimony whereof I have hereunto set my hand in the presence of two subscribing witnesses.

SAMUEL STEWART.
